SLICING MACHINE

William J. Campbell, Indianapolis, Ind., assignor
to American Slicing Machine Company, Chi-
cago, Ill., a corporation of New York

Application March 2, 1934, Serial No. 713,631

9 Claims. (Cl. 146—102)

My invention relates to an improvement in slicing machines and has for one purpose the provision of improved means for protecting the cutting edge of the knife when the device is not in use. Another purpose is the provision of means effective to support the work, during the cutting operation, at a point closely adjacent the cutting plane. Other objects will appear from time to time throughout the specification and claims.

I illustrate my invention more or less diagrammatically in the accompanying drawings, wherein—

Figure 1 is an elevation;

Figure 2 is a plan view;

Figure 3 is an end view;

Figure 4 is a section on the line 4—4 of Figure 1;

Figure 5 is a similar section with the parts in a different position;

Figure 6 is a section on the line 6—6 of Figure 5;

Figure 7 is a partial plan view similar to Figure 2 of a variant form of the device;

Figure 8 is a view similar to Figure 1 of the structure shown in Figure 7;

Figure 9 is a section on the line 9—9 of Figure 7;

Figure 10 is a partial section through a variant form.

Like parts are indicated by like symbols throughout the specification and drawings.

Referring to the drawings, A indicates any suitable base upon which may be mounted a motor A¹ which is adapted to drive, through a driving connection not herein shown, any suitable rotary knife A².

B indicates a guard plate for the forward face of the knife, herein shown as penetrating a forward hollow in the knife, the knife axis being somewhat tilted in order to permit this penetration.

C is any suitable gauge plate, mounted for example, on a support C¹ associated with guides C² and actuated by any suitable external hand lever or member C³, whereby the gauge plate may be moved toward and away from the cutting plane.

D indicates any suitable slice receiving member adapted to receive the slices which are severed by the action of the knife.

E indicates a work supporting carriage which is guided, for example, by tracks E¹, E², along a path extending across the face of the gauge plate C and past the cutting edge of the knife A². The carriage E is provided with a work receiving member E³ having a forward edge E⁴, spaced some-

what away from the cutting plane of the knife. It will be observed that the forward edge of the member E³ is provided with an undercut portion or recess E⁵. Slidable in said recess is the marginal work supporting member E⁶, which may be provided with a plurality of inclined edged upwardly extending work engaging blades E⁷. E⁸ indicates a guiding bracket mounted on the bottom of the member E³, and effective to guide a pin E⁹ secured to the member E⁶. The aperture in the member E³ adjacent the work supporting member E⁶ for guiding the pin E⁹ is preferably of corresponding diameter, whereas the opposite aperture may be elongated, as illustrated in Figure 6, to permit free lateral movement of the pins and to prevent binding due to irregular movement of the pins and associated parts. As many of these brackets and guides as are necessary may be employed but in Figures 1 and 2, I illustrate two. E¹⁰ is a coil spring; about each such pin E⁹ and E¹¹ is an abutment for said spring. E¹² is a movement limiting washer and E¹³ are a lock nut or nuts. It will be understood, as from Figures 4 and 5, that the spring E¹⁰ tends normally to thrust the member E⁶ into the forward position in which it is shown in Figure 5, its movement being limited by the washer E¹², which may be adjusted by rotation of the nuts E¹³. When the gauge plate C is moved into alignment with the cutting plane in order to mask the cutting edge of the knife A², it may thrust the member E⁶ against the compression spring E¹⁰ into the position in which it is shown in Figure 4. Thus the user, when the gauge plate is in slice gauging position, has a work support which may be adjusted closely to the cutting plane of the knife. Therefore the work is supported at its extreme forward edge and any tendency to sag down is prevented. This is important, as it prevents the formation of "tails" or the fringing out of the work where the user is cutting a body of relatively soft material, such as ham, roast beef, or the like. It also limits the frictional contact between the work and the gauge plate and knife which is caused by the dragging of an unsupported body of meat against gauge plate or knife. This reduction of the frictional contact reduces greatly any tendency to "lard" the knife or gauge plate. In cutting fat meat, such as ham or bacon, any increase in the frictional drag of the material tends very quickly to cause a fringing out or flowing out of the fats. Hence an adequate support of the work as close as possible to the plane is of great importance. I obtain this support, while at the same time

permitting the gauge plate to be moved into neutral or edge masking position when the device is not in use. This is of great importance, in as much as the cutting edge is exceedingly sharp.

5 In Figures 7, 8 and 9, I illustrate a variant mechanism for obtaining the same result. In this form in the place of the fixed work support E³, I provide a movable or yieldingly mounted work support G, which is provided, for example, with 10 a plurality of securing pins G¹ surrounded by springs G², which normally tend to hold the support G fixed in position on the carriage E. G³ are abutment washers for the pins G¹ and are controlled by nuts G⁴, whereby compression of 15 the springs G² may be controlled. G⁵ are any suitable abutment washers which may, if desired, be of fiber or hard rubber, in order to eliminate noise or friction. They are herein shown as mounted on bosses G⁶ extending upwardly from 20 the carriage E.

H indicates a work supporting member which underlies the forward edge of the support G. It will be noted that the edge of the support G is cut back somewhat from the cutting plane as will be clear from Figures 7 or 9. The member H is mounted on pins H¹ which are guided in any suitable guiding bosses or sleeves H² associated with the carriage E. H³ are springs tending normally to thrust the member H forwardly into the position in which it is shown in Figure 9. This movement may be adjustably limited as by the nuts H⁴ which may be adjusted on the member H. It will be observed that the member H has an upper inclined face H⁵, the upper edge 25 of which lies substantially in the plane of the top surface of the member G. It may, however, be slightly lower or slightly higher. The member H, with its upper face H⁵, serves the same function as the member E⁶ with its projections E⁷ as earlier described. When the gauge plate C is in gauging position, as in Figure 9, the spring H³ presses the member H forward into work supporting position closely adjacent the cutting edge of the knife. It may, of course, be adjusted closely 30 to the cutting edge by rotation of the nuts H⁴, which correspond to the adjusting nuts E¹³ of Figure 5. When the gauge plate is moved into knife masking position, the position in which it is shown in dotted lines in Figure 9, then the member H is thrust rearwardly against the compression of the springs H³. This rearward movement lifts or tilts the yieldingly mounted work support G into the dotted line position in which it is shown in Figure 9. In order to prevent slipping of large slabs of bacon or salt pork while being sliced, the work support member H may be provided with an upwardly projecting lug or finger H⁷, which may be integral with the member H or may be a separate member secured thereon. The meat tray G, as illustrated in Figures 7 and 8, is cut away as at H⁸ to permit longitudinal movement of the lug H⁷ of the work support member H.

65 It will be realized that while in my drawings I have shown an operative device, still many changes may be made in size, shape, arrangement and number of parts without departing materially from the spirit of my invention. I wish, therefore, that my showing be taken as in a large sense diagrammatic.

70 In particular, I wish it to be understood that whereas I show the main work support E³ or G overlying a marginal work support E⁶ or H, it is within the scope of my invention to have the main work support spaced somewhat away from

the marginal work support and, if desired, separated therefrom by a gap. I illustrate such a modification in Figure 10 wherein K indicates the marginal support, K¹, the main work support, K², the guide or plunger for the marginal support, and K³, the gap above alluded to. It will also be understood that where as I find it desirable to employ a marginal support, I do not wish to be limited in my claims to any particular width of marginal support. For example, if a support 10 is effective at the margin of the supporting means as a whole, namely; adjacent the cutting plane, it may be desirable and possible to have a relatively narrow support as shown at H or E⁶, or said support may be of very substantial width underlying a substantial part of the main support E³ or G.

In the use and operation of my device, it will be understood that the marginal support may extend close to or practically up to the cutting plane, it 20 being merely important that it does not contact the cutting edge of the knife when the carriage is given its cutting stroke. However, when the carriage is at initial position and when the user wishes to discontinue use of the machine, he can 25 move the gauge plate controlling handle into inoperative position. This thrusts the gauge plate so far forwardly toward and into the cutting plane of the knife that it engages the marginal support and thrusts it back against its yielding means until 30 the gauge plate may be in the dotted line position in which it is shown, for example, in Figure 9. In effect, the marginal work support is forced back from the cutting plane in order to make way for the gauge plate and to permit the gauge plate to 35 lie in the cutting plane and thus mask the cutting edge of the knife. It is important that the movable work support, which I show as a marginal support, extend immediately adjacent the cutting plane when the gauge plate is not in neutral position, but be movable away from the cutting plane 40 to make room for the gauge plate when the gauge plate is moved by the operator into neutral position.

The abutment H⁷ has for one function to compress a piece of bacon or such material between the vertical flange of the work support or carriage and the abutment. It is possible, for example, to compress pieces of bacon that are little wider than the distance from the abutment H⁷ to the vertical flange. As a practical example, I have employed a machine in which the said space is 11 $\frac{1}{2}$ inches but have successfully sliced on this machine bacon 11 $\frac{1}{2}$ inches wide. The abutment also prevents the meat from stretching in width and prevents or reduces any tendency to form fringes on the edge of the bacon as it moves across the gauge plate and knife. In other words, the abutment carries the edge of the bacon past the cutting edge of the knife and this feature, with its reduction of fringing and with its compression of the forward part of the work, adds materially to the efficiency of the machine.

I claim:

1. In a slicing machine, a base, a knife mounted on said base and means for actuating it, a gauge plate and means for actuating it, a carriage and means for guiding it across said gauge plate and past the cutting edge of the knife, and a marginal work support movably mounted on the carriage adjacent the edge nearest the cutting plane, yielding means tending normally to urge it toward the cutting plane, said marginal work support extending closely adjacent the cutting plane, the gauge plate being movable into position beyond

the cutting plane in the direction of the carriage, the yielding means being of such strength as to permit the marginal work support to recede from the cutting plane in response to contact of the gauge plate.

2. In a slicing machine, a base, a knife mounted on said base and means for actuating it, a gauge plate and means for actuating it, a carriage and means for guiding it across said gauge plate and past the cutting edge of the knife, and a marginal work support movably mounted on the carriage adjacent the edge nearest the cutting plane, and guiding means therefor, adapted to constrain it to generally horizontal movement, yielding means tending normally to urge it toward the cutting plane, said marginal work support extending closely adjacent the cutting plane, the gauge plate being movable into position beyond the cutting plane in the direction of the carriage, the yielding means being of such strength as to permit the marginal work support to recede from the cutting plane in response to contact of the gauge plate.

3. In a slicing machine, a base, a knife mounted on said base and means for actuating it, a gauge plate and means for actuating it, a carriage and means for guiding it across said gauge plate and past the cutting edge of the knife, and a marginal work support movably mounted on the carriage adjacent the edge nearest the cutting plane, and yielding means tending normally to urge it toward the cutting plane, and an extended work support overlying the marginal work support, yieldingly mounted on the carriage, said marginal work support extending closely adjacent the cutting plane, the gauge plate being movable into position beyond the cutting plane in the direction of the carriage, the yielding means being of such strength as to permit the marginal work support to recede from the cutting plane in response to contact of the gauge plate, the marginal work support being adapted to slide beneath the extended work support, the marginal work support including a portion adapted, when the marginal work support is at the limit of its movement toward the cutting plane, to lie substantially in the plane of the upper face of the extended work support.

4. In a slicing machine, a base, a knife mounted on said base and means for actuating it, a gauge plate and means for actuating it, a carriage and means for guiding it across said gauge plate and past the cutting edge of the knife, and a marginal work support movably mounted on the carriage adjacent the edge nearest the cutting plane, and yielding means tending normally to urge it toward the cutting plane, and an extended work support overlying the marginal work support, and yieldingly mounted on the carriage, said marginal work support being provided with an abutment member upwardly extending to a level above that of the normal work engaging surface of the extended work support, said extended work support being cut away to permit the projection of said abutment member.

5. In a slicing machine, a base, a knife mounted on said base and means for actuating it, a gauge plate and means for moving it toward and away from the cutting edge of the knife, the forward face of the gauge plate, when moved into forward position extending forwardly of the cutting plane of the knife, a carriage and means for guiding it across said gauge plate and past the cutting edge of the knife, and a marginal work support movably mounted on the carriage adjacent the edge nearest the gauge plate, said work support extending normally closely adjacent the

cutting edge of the knife and being rearwardly movable, in response to adjustment of the gauge plate into its most forward position, by contact with the gauge plate.

6. In a slicing machine, a base, a knife mounted on said base and means for actuating it, a gauge plate and means for moving it toward and away from the cutting edge of the knife, the forward face of the gauge plate, when moved into forward position extending forwardly of the cutting plane of the knife, a carriage and means for guiding it across said gauge plate and past the cutting edge of the knife, and a marginal work support movably mounted on the carriage adjacent the edge nearest the gauge plate, said work support extending normally closely adjacent the cutting edge of the knife and being rearwardly movable, in response to adjustment of the gauge plate into its most forward position, by contact with the gauge plate, and yielding means tending normally to hold it in its forward position adjacent the cutting plane.

7. In a slicing machine, a base, a knife mounted on said base and means for actuating it, a gauge plate and means for actuating it, a carriage and means for guiding it across the gauge plate and past the cutting edge of the knife, a marginal work support movably mounted on the carriage adjacent the edge next to the cutting plane, limit means for limiting the movement of said work support to a point closely adjacent but short of the cutting plane of the knife, yielding means tending normally to urge said work support toward the said limit, the gauge plate actuating means being adapted to move the gauge plate across the cutting plane and into contact with the marginal work support, said yielding means for the marginal work support being of such strength as to permit said marginal work support to recede from the cutting plane in response to movement of the gauge plate.

8. In a slicing machine, a base, a knife mounted on said base and means for actuating it, a gauge plate and means for actuating it, a carriage and means for guiding it across the gauge plate and past the cutting edge of the knife, a marginal work support movably mounted on the carriage adjacent the edge next to the cutting plane, limit means for limiting the movement of said work support to a point closely adjacent but short of the cutting plane of the knife, yielding means tending normally to urge said work support toward the said limit, the gauge plate actuating means being adapted to move the gauge plate across the cutting plane and into contact with the marginal work support, said yielding means for the marginal work support being of such strength as to permit said marginal work support to recede from the cutting plane in response to movement of the gauge plate, and an extended work support the forward edge of which overlies the marginal work support, a forward portion of the marginal work support lying in substantially the same plane as the upper surface of the extended work support, when the marginal work support is at its closest approach to the cutting plane.

9. In a slicing machine, a base, a knife mounted on said base and means for actuating it, a gauge plate and means for actuating it, a carriage and means for guiding it across the gauge plate and past the cutting edge of the knife, a marginal work support movably mounted on the carriage adjacent the edge next to the cutting plane, limit means for limiting the movement of said work support to a point closely adjacent but short of the

cutting plane of the knife, yielding means tending normally to urge said work support toward the said limit, the gauge plate actuating means being adapted to move the gauge plate across the cutting plane and into contact with the marginal work support, said yielding means for the marginal work support being of such strength as to permit said marginal work support to recede from the cutting plane in response to movement of the gauge plate, and an extended work support the forward edge of which overlies the marginal

work support, a forward portion of the marginal work support lying in substantially the same plane as the upper surface of the extended work support, when the marginal work support is at its closest approach to the cutting plane, the extended work support being provided with yielding means tending normally to draw its forward edge downwardly against the opposed portion of the marginal work support.

WILLIAM J. CAMPBELL.
